MOTOR GENERATOR SUSPENSION

Emil H. Piron, New York, N. Y., assignor to
 Transit Research Corporation, New York, N. Y.,
 a corporation of New York

Application February 18, 1937, Serial No. 126,408

4 Claims. (Cl. 248—22)

This invention relates to a mounting for a motor generator unit such as is used on trolley cars, the unit consisting of a motor generator set, an air compressor for brakes and general service and a blower for the car body ventilating system. The primary object of the invention is to provide an improved mounting or suspension for this unit which will prevent the transmission to the car body of short wave vibrations.

Where vibrations of short wave length are to be damped it has been found most effective to provide substantial deflection in the mountings for the vibrating parts in order to materially alter these vibrations. It is also recognised that an elastic material such as rubber has the inherent quality of sound-damping more or less proportionate to its softness. It is, therefore, a specific object of this invention to provide a frame for this entire unit and to support this frame by springing elements of elastic material such as rubber acting in shear.

Another object is to provide elastic springs as above described, in an arrangement such that they will permit a rocking or "floating" of the mass of the unit to best advantage as regards the center of gravity of the unit and the torque reaction from the compressor which is of the reciprocating piston type. Conversely it is an object to arrange the elements of the unit and their frame in such manner that this "floating" effect can be obtained to best advantage.

A further object is to provide elastic springing elements of improved type comprising semi-cylinders of rubber having semicylinders of metal surface bonded to the interior and exterior diametrical surfaces thereof, the metal semicylinders each being, in fact, slightly less than 180° each so that as two elements are placed about a load receiving shaft the elastic material may be compressed before insertion into a retainer of inverted cup shape provided therefor in the frame of the unit to be supported.

A further object is to provide a single removable unit comprising the motor, generator, fan and compressor.

Other objects and advantages will become hereinafter more fully apparent as reference is had to the accompanying drawing wherein my invention is illustrated by way of example and in which:

Fig. 1 is a top plan view of my improved support,

Fig. 2 is a section taken along the lines 3—3 of Fig. 1,

Fig. 3 is a section through one spring and spring mounting, and

Fig. 4 is a plan view of one of the springs.

I indicates an electric motor in coaxial driving relation with a generator 2 and a blower 3, all of which are rigidly mounted on one leg 4 of an L-shaped frame. The frame is suitably made up of parallel side rails 5 and rails 6 and 7, and intermediate straps or saddles 8. The end rail 7 and a second rail 9 fixed to at least one side rail 5 constitute the short leg of the L-shaped frame and support a reciprocating compressor 10. Secured on the crankshaft 11 of the compressor is a pulley wheel 12. The shaft of the motor 1 has a pulley 13 which is connected to the pulley 12 by a belt 14.

The reciprocations of the piston in the compressor 10 cause a periodic vibration of its support and a potential source of noise for the car body to which the frame, above described, is secured. In order to damp these vibrations and also any vibrations from the motor, generator and blower the frame is supported by elastic shear springs 15, 16, 17 and 18.

In order to make the most efficient use of these springs, I place three of the springs at one end of the supported mass and the other at the other end thereof whereby a "floating" action is obtained. The springs 15 and 16 are placed on opposite ends of the axis of the crankshaft 11. The springs 16 and 17 are substantially equally spaced from the axis A—A of the center of gravity of the entire supported mass. The axis of the spring 18 is intersected by the axis A—A.

The springs 15, 16, 17 and 18 are all of identical construction and consist of two halves or segments each composed of an inner and an outer half shell 19 and 20 each surface bonded to a semicylinder of elastic material 21 therebetween. The shells 19 and 20 are each of slightly less than 180° in circumference so that when two spring segments are assembled substantial radial compression may be imposed on the elastic material 21. The segments are assembled on a shaft 22 adapted to be secured to some portion 22 of a car body and, when compressed, are inserted into a cylindrical cup shaped opening. Openings are provided, as indicated above, in the members 6 and 7.

What is claimed is:

1. The combination of an L-shaped frame having a motor, generator and blower mounted in line thereon, a reciprocating compressor offset therefrom and mounted on the short leg of the L, the opposite end rails of said frame having

a plurality of inverted cup shaped openings therein, and a cylindrical spring comprising segmental elastic elements and an axial load receiving shaft inserted in each of said openings.

- 5 2. The combination of an L-shaped frame having a motor, generator and blower mounted in line thereon, a reciprocatory compressor offset therefrom and mounted on the short leg of the L, the cross rail at the outer end of the long leg of the L having an inverted cup-shaped opening formed therein with the axis thereof crossing the line of the center of gravity of said blower, generator, motor and compressor, the cross rail at the opposite end of said long side 10 extending along and forming a part of said short side, the last named cross rail having three inverted cup-shaped openings formed therein with the axes of the first and second thereof being on opposite sides of said line and equally spaced therefrom and with the axis of the third thereof being on opposite sides of the axis of said compressor from said first and second thereof.
- 15 3. The combination of an L-shaped frame having a motor, generator and blower mounted in line thereon, a reciprocatory compressor offset therefrom and mounted on the short leg of the L, the cross rail at the outer end of the long leg of the L having an inverted cup-shaped opening formed therein with the axis thereof

crossing the line of the center of gravity of said blower, generator, motor and compressor, the cross rail at the opposite end of said long side extending along and forming a part of said short side, the last named cross rail having three inverted cup-shaped openings formed therein with the axes of the first and second thereof being on opposite sides of said line and equally spaced therefrom and with the axis of the third thereof being on opposite sides of the axis of said compressor from said first and second thereof, and elastic shear springs residing in each of said openings comprising semi-cylinders of rubber in constant, substantial compression with the walls of said opening and an axial shaft therethrough. 15

4. The combination of an L-shaped frame having a motor, generator and blower mounted in line thereon, a reciprocatory compressor offset therefrom and mounted on the short leg of the L, three springs means supporting the short leg 20 of the L, the axes of the blower, motor and generator passing between the first and second of said three spring means, the axis of said compressor passing between the second and third thereof, and a fourth spring means supporting 25 the long leg of the L, said fourth spring means residing laterally between said axes and said second spring means.

EMIL H. PIRON.
